UNITED STATES PATENT OFFICE

152,684

DESIGN FOR AN EMERGENCY AUTOMOBILE
LIGHT

Joseph Feltz, Jersey City, N. J.

Application April 16, 1946, Serial No. 128,659

Term of patent 14 years

(Cl. D48—32)

To all whom it may concern:

Be it known that I, Joseph Feltz, a citizen of the United States of America, residing at Jersey City, county of Hudson, State of New Jersey, have invented a new, original, and ornamental Design for an Emergency Automobile Light, of which the following is a specification, references being had to the accompanying drawing forming a part thereof wherein:

I claim:

The ornamental design for an emergency automobile light, as shown.

JOSEPH FELTZ.
